UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 13,359, dated October 24, 1882.

Application filed September 25, 1882. Term of patent 3½ years.

To all whom it may concern:

Be it known that I, DAVID G. MELVILLE, of Medford, in the county of Middlesex and State of Massachusetts, have invented a certain new and original Design for Carpets, of which the following is a specification.

The nature of my design is fully shown in the accompanying photographic illustration.

The design is composed of the detached sprays of flowers and foliage, arranged as shown, and the Grecian and other borders partially concealed by said sprays.

I claim—

The design for a carpet, substantially as shown and described.

In testimony whereof I have signed my name to this specification, in the presence of two subscribing witnesses, this 18th day of September, A. D. 1882.

DAVID G. MELVILLE.

Witnesses:

WALTER J. GADSBY,
WILLIAM SCHMIDT.
